A. J. D. LENZ.
JUMP SPARK ELECTRIC GAS LIGHTER.
APPLICATION FILED OCT. 21, 1920.

Patented June 21, 1921.

Inventor:

Alvin J. D. Lenz,
By Cheever & Cox
Atty.

UNITED STATES PATENT OFFICE.

ALVIN J. D. LENZ, OF EVANSTON, ILLINOIS.

JUMP-SPARK ELECTRIC GAS-LIGHTER.

1,382,099.

Specification of Letters Patent. Patented June 21, 1921.

Application filed October 21, 1920. Serial No. 418,399.

To all whom it may concern:

Be it known that I, ALVIN J. D. LENZ, a citizen of the United States, residing at Evanston, in the county of Cook and State 5 of Illinois, have invented a certain new and useful Improvement in Jump-Spark Electric Gas-Lighters, of which the following is a specification.

This invention relates to mechanism for 10 lighting inflammable gases in such a manner that the person doing the lighting may stand at a distance from the point where the flame is to be created and thus escape all chance of injury therefrom. It is especially applied 15 cable in lighting ordinary gas lamps, stoves and grates.

The object of the invention is to provide 20 a device of this character which is very efficient as a lighter itself, which has the very important advantage of being practically 25 non-short-circuittable, and which is so constructed that if a child or someone else places a connecting device across the points where the spark takes place no shock is 30 received. The invention consists in means for carrying out the foregoing object which can be easily and cheaply made, which is satisfactory in use and is not readily liable to get out of order. More particularly the 35 invention consists in features and details of construction hereafter more fully set forth in the specification and claims.

Referring to the drawings in which like 40 numerals denote like parts throughout the several views,

Figure 1 is a transverse sectional view illustrating a conventional form of electric gas lighter having the special mechanism of this invention applied at the operating 45 end.

Fig. 2 is a plan view of certain parts of Fig. 1.

Fig. 3 is a side view of the igniting or 50 sparking coil detached from the handle; and

Fig. 4 is an end view of the structure shown in Fig. 3.

Fig. 1 shows a conventional form of handle 10 having through its center a tubular passage 12 entered by electric conducting wires 14, 16 and 17, the latter two of which are respectively connected to the switch terminals 18 and 19, adapted to be engaged by an opposite switch terminal 20 55 manipulated by a push handle or button 22. The wire 14 continues on through the left

hand end of handle 10 and through the center of insulated block 24 until it terminates at the left hand end of the latter member in one firing contact 26. The block 24 is 60 made cylindrical at its left hand end and of an enlarged conical form at its right hand end so that a coil 30 of bare conducting wire may be inserted on it from the left and drawn to the position shown by the conductor's pulling on its end 32 until it can be secured in position by means of screw 34 by which it is attached to switch member 20. The opposite or effective end 36 of coil 30, which may be termed the igniting or 65 sparking coil, is bent inward to the right a substantial distance from the end convolution 40 of the coil 30 until it is separated from terminal 26 by the usual jump space or gap 38 across which electric charges may 70 pass in the usual manner when a properly constructed machine for producing such discharges is attached beyond the right hand end of Fig. 1 through the wires 14, 16 and 17. This turning the end 36 of the coil 30 75 inside the coil has two very important advantages. The first is that the jump space 80 38 is generally protected by the outer convolutions of the coil 30, thereby preventing foreign objects from getting in between terminals 26 and 36 and short circuiting the device. The second is that when a small 85 boy or other mischievous person places a metal rod or nail in the end of the coil 30 to investigate the points 26 and 36 and does 90 actually connect them he cannot make this connection without the object he carries touching the end convolution 40 of the coil with the result that the current in the inserted member is carried back directly to 95 coil 30, thus preventing any part of the current passing through the fingers or body of the person manipulating the instrument thus avoiding all chance of shock.

The end coils of the member 30 about 100 spark gap 38 are spaced apart slightly as shown so as to allow the free passage of gas into contact with the terminals 26 and 36 when the operator holding handle 10 places the device in the gas stream. 105

Having thus described my invention what I claim as new and desire to secure by Letters Patent, is:—

1. In a device of the class described, a central terminal adapted to be supplied with 110 electric energy and a coil of conducting material about and clear of said central termi-

nal extending beyond the end of said terminal, the end of said coil extending inwardly in the coil to a point in proximity to the first terminal, for the purposes set forth.

5. 2. A device of the character described comprising a coiled conductor having a terminal thereof turned inwardly within the coil, a second conductor having a terminal thereof spaced from said first terminal to thereby 10 provide a spark gap protected by the convolutions of the coil, and means for controlling the flow of electric current across said gap.

3. A device of the character described comprising a handle having a tapered portion, a 15 coiled conductor adapted for engagement over the tapered portion of said handle whereby it is retained in proper relation with respect thereto, a second conductor having one terminal thereof spaced relative to a terminal of the coiled conductor to provide a 20 spark gap, and means for controlling the flow of electric current across said gap.

4. A device of the character described comprising a handle, a coiled conductor carried 25 by and extending beyond one end of said handle, a terminal of said conductor being turned inwardly toward the handle and dis-

posed within the convolutions of the coil, a second conductor having a terminal thereof spaced from said first terminal to provide 30 a spark gap, and means for controlling the flow of electric current across said gap.

5. A device of the character described comprising a handle, a conductor extending through said handle and terminating adjacent to one end thereof, a second coiled conductor engaged over the handle and extending beyond one end thereof, means for securing 35 said coiled conductor to the handle, a terminal of said coiled conductor being turned inwardly within the convolutions of its coils and disposed in spaced relation to a terminal of the first conductor to provide a 40 spark gap, the convolutions of the extending portion of the coiled conductor being spaced relative to each other, and switch means carried by the handle for controlling the flow of 45 electric current across said gap.

In witness whereof, I have hereunto subscribed my name in the presence of a witness.

ALVIN J. D. LENZ.
